UNITED STATES PATENT OFFICE

166,740

TROPHY BASE

Ray Edgar Dodge, Los Angeles, Calif.

Application June 4, 1951, Serial No. 15,417

Term of patent 14 years

(Cl. D29—23)

To all whom it may concern:

Be it known that I, Ray E. Dodge, a citizen of the United States and a resident of Los Angeles, county of Los Angeles, State of California, have invented a new, original, and ornamental Design for a Trophy Base, of which the following is a specification, reference being had to the accompanying drawings, forming part hereof and in which:

Fig. 1 is a front perspective view of a trophy base, showing my new design.

Fig. 2 is a front elevational view thereof.

Fig. 3 is a top elevational view thereof.

I claim:

The ornamental design for a trophy base, substantially as shown.

RAY E. DODGE.
